UNITED STATES PATENT OFFICE.

AUGUST KADOW, OF TOLEDO, OHIO, ASSIGNOR TO THE LIBBEY GLASS MANUFACTURING COMPANY, OF TOLEDO, OHIO, A CORPORATION OF OHIO.

METHOD AND APPARATUS FOR FORMING GLASS STEMWARE.

Application filed November 10, 1922. Serial No. 600,051.

To all whom it may concern:

Be it known that I, AUGUST KADOW, a citizen of the United States, and a resident of Toledo, in the county of Lucas and State of Ohio, have made an Invention Appertaining to a Method and Apparatus for Forming Glass Stemware; and I do hereby declare the following to be a full, clear, and exact description of the invention, such as will enable others skilled in the art to which it appertains to make and use the same, reference being had to the accompanying drawings, and to the characters of reference marked thereon, which form a part of this specification.

This invention relates to the manufacture of glass articles, and particularly to that class of articles known as stemware. In the manufacture of articles of this class it has been customary to form the bowl and stem portions separately and to then attach or unite the two, or if the articles are formed or molded from a single gather of glass by either pressing or blowing the gather, such forming of the stem, foot and bowl portions of the article has taken place in a different mold or molds from that in which the original blank is gathered.

An object of the invention is to simplify the manufacture of glassware of this character by forming the foot and stem portions thereof complete in the gathering mold or head and subsequently developing the blank portion at the outer end of the stem to form the bowl of the article.

The invention is fully described in the following specification, and while, in its broader aspect, it is capable of embodiment in numerous forms, a preferred embodiment thereof is illustrated in the accompanying drawings, in which,—

Figure 1 is a fragmentary vertical section of a machine embodying the invention showing a gathering unit and an associated blank receiving and blowing unit in the act of receiving a blank from the gathering unit, with the body mold open and with parts broken away. Fig. 2 is an enlarged plan view of the forward end portion of the gathering unit with the body molds in open position. Fig. 3 is an enlarged plan view of the neck molds of the gathering unit with a portion of the associated operating means. Fig. 4 is a front end elevation of one of the gathering horns of the gathering mechanism

with the associated neck mold sections in closed position and with the blank mold sections removed. Fig. 5 is an enlarged side elevation of the forward end portion of the gathering mechanism with parts broken away, with the body molds open and with the blank carrying portion of a blowing unit in the act of receiving a blank from the gathering unit. Fig. 6 is a plan view of one of the body molds in open position. Fig. 7 is an enlarged sectional fragmentary view of the blow pipe of a blowing unit and finishing mold in associated relation. Fig. 8 is a view similar to Fig. 1 with the gathering mechanism in longitudinal section, the gathering mold sections open, and with the blow pipe of the blowing unit fragmentarily shown and in the act of taking the blank away from the gathering unit. Fig. 9 is a sectional view illustrating the initial blowing step in the operation. Fig. 10 is a similar view illustrating the partially blown blank before inserting into the finishing mold, and Fig. 11 is a fragmentary elevation of the gathering end of the gathering unit with the associated mold sections in closed relation and containing a gather.

In carrying out the method embodying this invention, the blank is gathered from a source of molten glass by means of a suction head, which gives the final shape to the stem or the stem and foot portion of the ware, such for instance, as tumblers, and the initial shape to the bowl portion thereof. The bowl is then released by the body and neck molds and engaged by a spindle or blow-pipe, after which a plunger is forced into the bowl portion of the blank to form a depression at the outer end thereof in the axial line of the blank. Puffs of air are then introduced into the blank through the spindle to gradually develop the blank. The bowl portion of the blank is then placed in a finishing mold and blown to its final shape. The article may then be finished in the regular way by annealing, cracking off, grinding and polishing.

The mechanism preferably employed for practicing the invention is of the general type of glass working machines disclosed in my former U. S. Letters Patent Nos. 1,223,393, 1,248,664 and 1,195,588, with some parts modified or changed to suit the requirements of the invention. This type of forming machine comprises a rotating struc-

ture provided with one or more glass gathering units which are periodically brought to a point opposite the working opening of a stationary glass furnace and are thrust into such opening to make the successive gathers. When the blanks have been formed in this way they are delivered to spindles or other mechanisms for further treatment, said device being preferably carried on the same rotative structure which supports the carrying mechanism so that the manufacture of the article is completed by a series of automatic operations which are carried out by different parts of the single machine.

15 Referring to the drawings, 1 designates the rotary structure of a machine for practicing the invention, which structure is adapted to support a number of glass gathering units. This structure also carries a 20 spindle or blow-pipe 2 for each gathering unit arranged to receive the glass blanks after they have been gathered and partially formed by the gathering unit.

The glass gathering ram 3 of each gathering unit is mounted for reciprocatory movements on an inclined support 4, which is fixed to the rotary structure 1 of the machine radially thereof. The ram is shown as provided with two gathering horns 5, so 30 that two gathers may be made simultaneously, and each horn is provided with a set of neck molds 6 and a set of body molds 7, which cooperate to form the gathering head or blank receiving cavity of each ram horn. 35 The ram of each gathering unit has reciprocatory movements imparted thereto when in register with the working opening of the associated furnace to quickly project the ram into the furnace to receive a gather and then to retract it into position to deliver the gather to the associated spindle 2. A suitable mechanism for imparting reciprocatory movements to the ram is disclosed in Patent No. 1,223,393.

45 Each neck mold 6 comprises two halves which are hinged together at 8 and when closed seat around a flange 9 (Figs. 5 and 8) on the lower edge of the respective horn 5 to closely embrace the same and cooperate therewith to form a cavity for receiving and forming the foot *a* and adjacent portion of the stem or neck *b* of a blank. The sections of each neck mold 6 have arms 10 (Fig. 3) projecting therefrom in opposite directions and connected by a set of toggle links 11 to the adjacent end of a cross-bar 12, whereby a rearward pull on the cross-bar will retain the neck molds closed and a forward movement of the cross-bar will cause an 55 opening of such molds. The cross-bar 12 is connected at its center through the medium of a link 13 to the forward end of an operating rod 14 (Fig. 8), which extends rearward through the ram 3, being guided 60 for longitudinal reciprocatory movements

therein and carrying a roll 15 at its rear end in position to be engaged by a cam 16 on a stationary part 17 of the machine structure when the rotary structure is at a predetermined point in its rotary movement, or in other words, when the gathering ram has reached a point in its cycle of movement at which it is desired to release the neck molds from engagement with the blank foot. A spring 18 acts on the rod 14 to normally hold it retracted in mold closing position.

Each of the body molds 7 comprises two sections or halves hinged together on a vertical axis 19 (Fig. 6) with the sections 80 cooperating to give the finished shape to the stem *b* of the blank and the initial shape to the bowl portion *c* thereof. The mold sections, when closed, seat closely around a lower edge flange of the neck mold 6. The 85 sections of each body mold are connected together in spaced relation to the pivot 19 by a pair of toggle links 20, which are pivotally connected at their inner ends to a coupling 21 that is in turn connected to the lower end 90 of a vertically disposed lever 22. One of these levers is provided for each body mold and is fulcrumed at 23 to the respective ram horn 5. The upper end of the lever is connected by a link 24 to the forward end of a 95 push rod 25, which is mounted in a respective bearing 26 for reciprocatory movements longitudinally of the ram. A coiled compression spring 27 is mounted on each rod 25 between the rear side of the bearing 26 100 and a shoulder on the rod and acts on the body mold operating mechanism to normally retain the body molds closed. The body molds are intended to remain closed during a movement of the gathering means 105 into the furnace and until the ram has been retracted to near the limit of its rearward stroke when the rear ends of the push rods 25 will engage respective spring pressed buffers 28 carried by the ram guide structure 4 and be moved thereby to effect an 110 opening of the body mold, the open position of such molds being maintained until the ram is again moved forward to receive a gather.

115 A cut-off knife 29 is provided for each gathering head to remove the surplus glass from the inlet end of the body mold after the gathers have been made. The mechanism for operating the cut-off knives is the same as that shown and described in my former Patent 1,208,791 and need not therefore be specifically described herein. It will also be understood that the means for creating a suction within the gathering heads to gather the glass therein and the suction release means may be the same as that disclosed in said Patent 1,195,588.

120 The spindles 2 of each blowing unit are provided in pairs to take care of the two 130

gathers of an associated ram 3 and the spindles of each pair are mounted for vertical turning and swinging movements, to adapt them to receive the respective gathers from the ram when the free ends of the spindles are in upright position and then to swing or turn to lowered position preparatory to placing the gathers or blanks held thereby in the finishing molds, all of which operations are well understood in the art. A blank is clamped to the head or blowing end of the spindle by a set of jaws 30 which engage a flange *d* formed around the edge of the blank bowl. When the blank has been engaged by a spindle a plunger 31 in the spindle is operated to form a central depression in the outer end of the blank body and is then retracted to permit puffs of air to be blown into the depression from the spindle to properly develop the blank. During or prior to the development of the blank in this manner, it is swung by the spindle to lowered position and is later placed in a finishing mold 32 (Fig. 7). Prior to the closing of the mold sections 32 around the blank, which closing is effected in any suitable or well known manner, as is common in machines of this class, the foot *a* of the blank rests on a support 33 and thereby supports the weight of the blank and prevents a lengthening thereof due to gravity.

When the blank bowl has been brought into the desired shape within the finishing mold 32, the blank is removed from the spindle and finishing mold and is then finished in the regular way by annealing cracking off, grinding and glazing substantially along the line *e*—*e* in Fig. 7.

The operation of my method is as follows: A blank having been gathered within the molds 6 and 7 in the usual or any suitable manner, the body molds 7 are first opened to permit the transfer of the blank to the blowing spindle, as indicated in Figs. 1 and 5, which spindle may be handled mechanically or by hand. Before the jaws of the spindle are clamped to the blank the neck mold 6 is opened slightly to allow the blank to hang loosely by the foot, thereby permitting the blank to accommodate itself to the position of the spindle. When the blank leaves the gathering molds the foot and stem portions *a*, *b* thereof are in finished form and the bowl *c* is in blank form to be finished by the subsequent operations. The next steps in the development of the blank bowl may be accomplished in the up vertical position, the horizontal position or the down vertical position of the article depending on the size, weight and shape of the blank. Fig. 8 shows the blank as leaving the gathering head and the plunger 31 of the spindle has moved into the blank to leave a depression in the glass exactly on its axis when withdrawn. The

next step in the development, illustrated by Fig. 9, is the introduction of a measured quantity of air under a predetermined pressure through the spindle and into the depression in the glass to expand the soft bowl portion of the blank. The number of these puffs and the pressure used is determined by the size and shape of the article and temperature of the glass. Before the final blowing of the article the spindle is brought to the down vertical position shown in Fig. 10 where the blank is blown out enough to allow the foot to settle upon the bottom plate 33 of the finishing mold 32. The finishing mold is then closed around the blank and the final blowing of the article is performed as shown in Fig. 7, after which the article is removed from the finishing mold and spindle and the outer end portion of the bowl broken off and the bowl edge finished in the regular or any suitable manner.

It is evident with my process that the stem foot and bowl of an article of the stem ware type is formed from a single gather, the foot and stem being formed completely by the gathering mold while the bowl of the article is finished by subsequent blowing and shaping operations. In the finishing of the bowl the previously formed foot and stem perform an important function in supporting or limiting the downward elongating action of the article when it has lengthened a predetermined extent.

While I have illustrated my method as being practiced by mechanical means, it is evident that it may be accomplished by hand or by numerous other means than that illustrated and that the method itself as illustrated and described may be varied materially without departing from the scope of the claims.

Having thus described my invention, what I claim as new and desire to secure by Letters Patent, is,—

1. The process which consists in sucking glass into a mold, allowing one end of said glass to set in the shape given it by the suction mold, and blowing into the other end of said glass to expand it before it is set.

2. The process of forming stemmed glass-ware, which consists in forming a stem by sucking glass into a mold, and then forming the bowl by blowing glass integral with the stem.

3. The process of making stemmed glass-ware, which consists in sucking glass into a mold and thereby forming a blank having the stem in final shape and bowl in unexpanded form, and thereafter expanding the bowl portion.

4. The process of forming stemmed glass-ware, which consists in forming a stem in final shape, with a bowl blank integrally attached, by sucking glass into a mold, and

then blowing the bowl blank to final form.

5. The process of forming stemmed glassware, which consists in forming a solid blank having the stem in final shape with the bowl blank integrally attached, then supporting the blank entirely from the end opposite the stem while forming the solid bowl blank into a parison, and finally blowing the parison.

10 6. The process of forming stemmed glassware, which consists in gathering glass directly from a molten mass into forming means and thereby forming a stem in final shape with a bowl blank attached, and thereafter giving the bowl blank final shape.

7. The method of forming stemmed glassware, which consists in forming a stem in final shape with a bowl blank integrally attached by gathering a definite quantity 20 of glass directly from a molten mass into blank forming means, shearing the gather from the mass, and then blowing the bowl blank by means engaging the sheared portion of the gather.

25 8. The process of forming glass articles, which consists in gathering glass from a molten mass, giving one end of the gather final form while the other end is still attached to the mass, shearing the gather from the mass, engaging the sheared end of the gather with blowing means, and then completing the shaping.

9. The process of forming stemmed glassware, which consists in gathering glass from a molten mass, giving one end of the gather the final form of a stem while the other end is still attached to the mass, shearing the gather from the mass, and then shaping the bowl.

40 10. The process which consists in sucking a gather from a mass of molten glass, giving the portion first sucked up final form by sucking it into forming means, severing the gather from the mass, removing the gather from the forming means, engaging the severed end of the gather with blowing means, then forming a blow opening, and finally blowing.

11. The method of forming glass articles, 50 which consists in forming a blank by gathering a definite quantity of glass directly from a molten mass into blank forming means, shearing from the mass the glass thus gathered, delivering the blank bodily from the forming means so as to have the sheared end in engagement with a blowing means, and then expanding a portion of the blank adjacent the blow pipe while leaving the opposite end in the form given it by said forming means.

65 12. The process of forming glass articles, which consists in gathering a definite quantity of glass directly from a molten mass into forming means, shearing the formed gather from the mass, engaging the sheared

end of the gather with blowing means, and then blowing the intermediate portion of the gather while leaving the walls adjacent the sheared end and the end of the blank opposite the sheared end in the form given 70 them by said means.

13. The method of forming blown stemware which consists in gathering a predetermined quantity of molten glass in a mold by which the stem and foot portions of the article are formed complete and the bowl portion thereof blanked out, then releasing the bowl forming portion of the mold from the blank, forming a depression in the outer end of the blank bowl, engaging a blowpipe to the outer end of the bowl blank, releasing the stem and foot portions of the article from the gathering mold and blowing the bowl portion of the article to predetermined shape, the bowl being encased within 80 a finishing mold during the final blowing operation, and then trimming and finishing the outer end portion of the bowl.

14. In an apparatus of the class described, a gathering ram, sectional neck molds and sectional body molds carried by the ram and cooperating therewith to respectively form the stem portion of an article complete and to blank out the bowl portion thereof, and separate means operable to independently 90 open and close the neck mold sections and the body mold sections.

15. In an apparatus of the class described, a reciprocally movable ram, blank gathering means carried by the ram and comprising 100 a sectional neck mold and a sectional body mold with the sections thereof hingedly carried by the ram for opening and closing movements, the neck mold and the body mold cooperating to form the foot and stem portions of an article complete and the body mold being operable to blank out the bowl portion of the article, and means independently operable at predetermined points in 105 movements of the ram to open and close the neck mold sections and the body mold sections.

16. In an apparatus of the class described, a gathering ram, a sectional neck mold and a sectional body mold carried by the ram and cooperating therewith to respectively 115 form the stem portion of an article complete and blank out the bowl portion thereof, separate means operable to independently open and close the neck mold sections and the body mold sections, and means operable to shape the bowl portion of the article after being released by the neck and body molds.

17. In an apparatus of the class described, a gathering ram, a sectional neck mold and a sectional body mold carried by the ram and cooperating therewith to respectively 120 form the stem portion of an article complete and blank out the bowl portion thereof, separate means operable to independently 125

open and close the neck mold sections and the body mold sections, and means operable to take the article from the neck and body mold and pneumatically act on the bowl portion of the article to shape the same.

18. In an apparatus of the class described, a reciprocally movable ram, blank gathering means carried by the ram and comprising a sectional neck mold and a sectional body mold 10 with the sections thereof hingedly carried by the ram for opening and closing movements, the neck and body molds cooperating to form the foot and stem portions of an article complete and the body mold being 15 operable to blank out the bowl portion of the article, means independently operable at predetermined points in movements of the ram to open and close the neck mold sections and the body mold sections, and 20 means operable to shape the bowl portion of the article after being released by the neck and body mold.

19. In an apparatus of the class described, a reciprocally movable ram, blank gathering 25 means carried by the ram and comprising a sectional neck mold and a sectional body mold with the sections thereof hingedly carried by the ram for opening and closing movements, the neck and body molds co- 30 operating to form the foot and stem portions of an article complete and the body mold being operable to blank out the bowl portion of the article, means independently operable at predetermined points in movements of 35 the ram to open and close the neck mold

sections and the body mold sections, and means operable to take the article from the neck and body mold and pneumatically act on the bowl portion of the article to shape the same.

20. In an apparatus for forming blown glass stemware, means for gathering a quantity of molten glass and shaping a portion of the same to form the stem of the article complete and another portion to form the 40 bowl blank of the article, means for taking the article from the gathering means and blowing the bowl portion thereof into predetermined shape, a finishing mold receiving the bowl blank during the final blowing 45 operations, and means forming a support on which the base of the stem portion of the article rests during a predetermined portion of the blowing operation.

21. In an apparatus for forming blown 50 glass stemware, means for gathering a quantity of molten glass and shaping the same to form the foot and stem portions of an article complete and blanking out the bowl 55 portion thereof, means for taking the article from the gathering means and blowing the bowl portion thereof to predetermined shape, and means subjacent to the article and on which its foot rests during a predetermined portion of the bowl blowing 60 operation.

In testimony whereof I have hereunto signed my name to this specification.

AUGUST KADOW.
